UNITED STATES PATENT OFFICE.

SAXTON J. MORGAN, OF ALBANY, WISCONSIN.

HACKSAW-FRAME.

1,395,511.

Specification of Letters Patent.

Patented Nov. 1, 1921.

Application filed June 25, 1919. Serial No. 306,513.

To all whom it may concern:

Be it known that I, SAXTON J. MORGAN, a citizen of the United States, residing at Albany, in the county of Green and State of 5 Wisconsin, have invented certain new and useful Improvements in Hacksaw-Frames, of which the following is a specification.

My invention relates to improvements in frames for holding hack saws, especially 10 for hand use, although a frame embodying the principles of my invention is also well adapted to carry the saw in a power-driven sawing machine.

One of the objects of my invention is to 15 provide quickly releasable clamping means whereby the saw can be tightly clamped in position or released and removed in an instant.

Another object of my invention is to 20 construct such a frame entirely out of sheet metal and bars without the use of any cast material.

Further objects and advantages of my invention will become apparent as the description 25 proceeds.

In the accompanying drawings, Figure 1 is a side view of a hack saw frame embodying the principles of my invention. Fig. 2 is a section on the line 2—2 of Fig. 1, and 30 Fig. 3 is a perspective view of the sleeve for the rear bolt.

A device according to my invention comprises a handle, an arm telescopically mounted in said handle and two retaining 35 bolts for the saw blade. In the embodiment of my invention selected for illustration the handle, designated as a whole by the reference character A, comprises a main U-shaped frame 10 formed by bending an H-shaped 40 sheet horizontally along its center line to form a tubular portion 11 adapted to receive the arm B in sliding engagement. Each flap of the main frame is cut to the shape illustrated in Fig. 1, and the two flaps 45 are held together throughout the hand grip by engagement between the handle pieces 12 which are clamped on by suitable screws 13 and throughout the front downward projection 14 by suitable rivets. The forward 50 arm of the main frame member A terminates at 15 (see Fig. 2) and is continued down by a U-shaped sheet metal extension 16 com-

prising a cylindrical portion 17 and two upwardly extending arms 18 suitably riveted to the main frame.

The arm B extends through the handle A forward and downward and carries a sleeve 19 generally similar to the extension member 16 and adapted to embrace the front bolt C. Adjustment of the arm B over a considerable 55 range is provided by a plurality of holes 20 drilled at intervals along the arm as shown in Fig. 1. A locking pin 21 carried by a leaf spring 22 is resiliently held by the said spring in the position shown in Fig. 2. The 60 arm B may thus be locked in any one of a plurality of adjusted positions. A second and more precise adjustment is provided by an adjustable mounting for the bolt C in the sleeve 19. A collar 23 carries a lug 24 engaging in a notch in the sleeve and is thus 65 prevented from rotation. The collar carries a key slidably engaging in the slot 25 in the bolt C to restrain said bolt from rotation. Notches to receive the lug 24 are cut at 70 75 ninety degree intervals in the sleeve 19 for a purpose to be referred to later. A nut 26 engaging the screw threads on the bolt C has ample bearing surface against the collar 23 to take the tension in the hack saw blade. A 80 small locking nut 27 at the opposite end of the sleeve 19 holds the bolt C in position when the blade is removed. The threaded portion of the bolt C is long enough to provide a range of adjustment substantially 85 equal to the distance between adjacent holes 20. Exact adjustment of the position of the bolt C over the entire range is thus obtainable. Bolt C carries the usual pin 28 slightly inclined forwardly, and the rear sliding bolt 90 D carries a similar pin 29.

Quickly releasable clamping means are provided for drawing the bolt D back through the sleeve formed by the cylindrical portion of the extension to clamp and 95 tension the hack saw blade. As shown, the central portion of the sleeve 16 is cut away at the center leaving two loops 16^a. A sleeve 30 (see Fig. 3) fits loosely within these loops for sliding axial movement. The 100 sleeve 30 receives the rear bolt D which is prevented from sliding through the sleeve by a small pin 31; notches 32 in the rear end of the sleeve 30 receive the pin 31 in any

one of four different positions spaced ninety degrees apart and prevent rotation of the bolt D in the sleeve.

The pins 28 and 29 project from the flat 5 sided semi-cylindrical ends of the bolts C and D respectively, and the ends of both bolts may be positioned in any one of four different positions by means of the pin 31 and lug 24 to allow the blade 39 to cut in 10 the corresponding direction.

A compression spring 33 surrounding the sleeve D and engaging the faces of a shoulder 34 on the projecting front end of the bolt, and a washer 35, resiliently presses the 15 bolt D forward and normally retains the pin 31 in the slots 32. A lug 36 on the sleeve 30 formed by two projecting ears integral with the cylindrical portion of the sleeve slides in the slot defined by the arms 20 18 of the projection 16. The front face of the lug 36 engages the sloping surface of a cylindrical cam 37 surrounding the sleeve 30 and restrained from endwise motion by 25 engagement with the faces of the loops 16a. The cam 37 carries a projecting lever 38 adapted to be manually engaged to rotate 30 said cam. As illustrated in Fig. 2, the lever extends on a line offset from the center of rotation of the sleeve so as to lie flat against 35 the side of the handle member A. The cam 37 has a helical portion extending partway around its periphery and terminating in a flat portion adjacent the lever 38. The lever and cam are one integral piece of material. 40 In the position shown in Fig. 1, the lug 36 bears against the flat portion of the cam 37 and the tension of the blade 39 holds 45 the parts securely in position by friction.

With the arm B and bolt C properly adjusted for the length of blade being used, the 40 blade can be removed from the saw by rotating the cam lever 38 270 degrees to the position shown in dotted lines in Fig. 2, allowing the spring 33 to move the bolt D and 45 sleeve 30 forward. This movement allows the blade 39 to fall freely off the inclined pins 28 and 29 and a new blade may be laid over them and quickly stretched to the desired tension by returning the cam lever 38 50 to its locking position.

An advantageous feature of my construction, especially with regard to the cost of production and to the durability and service, is that no castings are used in any part 55 of my device. The two bolts C and D can be readily machined from rolled rods and all the other parts stamped or cut out and bent to shape from rolled sheet material. The H-shaped blanks necessary to form the 60 handle member A are so shaped that the projecting legs of one H may be stamped from the material corresponding to the space at the side of another H whereby considerable saving of material results. The 65 rear side of the depending handle grip is

suitably shaped to be engaged by the hand of the workman, and this shape is conveniently continued by the upwardly sloping end 40 at the rear end of the arm B.

While I have shown and described in detail a specific embodiment of my invention, it should be clearly understood that the description is illustrative only and that many modifications and improvements will naturally occur to persons skilled in the art. 75 I aim in the subjoined claims to cover all such legitimate modifications and improvements.

I claim as my invention—

1. A hack saw having, in combination, a 80 frame, a fixed bolt and a slideable bolt carried by said frame, means on said bolts for engaging the ends of the hack saw blade, quickly releasable clamping means for sliding said slideable bolt, and resilient means 85 urging said slideable bolt into position to release said blade.

2. In a hack saw frame, a one piece handle member and bolt support member comprising a single piece of sheet metal cut to an 90 H shape, and folded horizontally along the center line of the cross piece of the H.

3. In a hack saw, in combination, a sleeve, a saw straining bolt in said sleeve, resilient means urging said bolt in one direction, and 95 a cam adapted to draw said bolt in the opposite direction.

4. In a device of the class described, a handle, a bolt having means to engage one end of a hack saw blade, a sleeve on said 100 bolt, means for limiting the sliding motion of said sleeve on said bolt, a lug on said sleeve adapted to engage a slot in said handle and prevent said sleeve from rotating, and a cylindrical cam rotatable on said 105 sleeve engaging one face of said lug.

5. In a device of the class described, a handle member carrying a sleeve, said sleeve having radially extending portions defining a radial slot, a slideable sleeve in said first-mentioned sleeve having a lug sliding in said radial slot, an annular cam member surrounding said slideable sleeve and engaging the edge of said lug, said first-mentioned sleeve being cut away to form a transverse 110 slot receiving said annular cam member and restraining it from endwise motion.

6. In a hack saw frame, a one piece handle member and bolt support member comprising a single piece of sheet metal cut 115 to an H shape, and folded horizontally along the center line of the cross piece of the H, the cross piece of said H being bent tubular and the sides of said H lying in contact to form a handle portion and a bolt supporting 120 portion respectively.

7. In a device of the class described, in combination, a handle member having downwardly extending spaced parallel walls terminating in two longitudinally spaced 125

loops, a sleeve slideable in said loops, a lug on said sleeve projecting between said walls to restrain said sleeve from rotation, an annular cam encircling said sleeve and slidably engaging said loops, said cam being adapted to engage said lug, and means for rotating said cam.

8. In a device of the class described, in combination, longitudinally extending spaced parallel walls, a pair of longitudinally spaced loops joining the lower edges of said walls, a bolt slideable in said loops, projecting means carried by said bolt and engaging between said walls, and a rotatable annular cam encircling said bolt between said loops and adapted to engage said projecting means to slide said bolt.

9. In a hack saw frame, in combination, a handle member, an arm telescoping in the upper portion of said handle member, the rear end of said arm being cut at an angle, to conform to and prolong the contour of the rear edge of said handle member.

10. A device of the class described comprising a handle, a bolt for engaging one end of a hack saw blade, a sleeve on said bolt having slideable engagement in said handle, means to prevent rotation of said sleeve relative to said handle comprising a lug on said sleeve arranged to engage in a slot in said handle, a pin in said bolt projecting radially therefrom, a plurality of notches provided in the end of said sleeve to receive said pin, resilient means for urging said bolt into position to release said blade, and means engaging the lug on said sleeve adapted when actuated to move said bolt to communicate a straining stress to the hack saw blade comprising a cylindrical cam rotatable on said sleeve and a lever for rotating said cam.

11. A device of the class described comprising a handle, a bolt for engaging one end of a hack saw blade, a sleeve on said bolt having slideable engagement in said handle, means to prevent rotation of said sleeve relative to said handle, a pin in said bolt projecting radially therefrom, a plurality of notches provided in the end of said sleeve to receive said pin, resilient means for urging said bolt into position to release said blade, and means adapted when actuated to move said bolt to communicate a straining stress to the hack saw blade comprising a cylindrical cam rotatable on said sleeve, and a lever for rotating said cam.

12. A device of the class described comprising a handle, a bolt for engaging one end of a hack saw blade, a sleeve on said bolt having slideable engagement in said handle, means to prevent rotation of said sleeve relative to said handle, a pin in said bolt, a plurality of notches provided in the end of said sleeve to receive said pin, means for urging said bolt into position to release said blade, and means adapted when actuated to move said bolt to communicate a straining stress to the hack saw blade.

13. A device of the class described comprising a handle, a bolt for engaging one end of a hack saw blade, a sleeve on said bolt engaging in said handle, means to prevent rotation of said sleeve relative to said handle, and means for permitting adjustment of said blade to any one of a plurality of cutting planes, comprising a pin in said bolt and a plurality of notches provided in the end of said sleeve for receiving said pin.

In testimony whereof I have hereunto set my hand.

SAXTON J. MORGAN.
